UNITED STATES PATENT OFFICE.

JOHN F. O'CONNOR, OF CHICAGO, ILLINOIS, ASSIGNOR TO WILLIAM H. MINER, OF CHAZY, NEW YORK.

DYNAMOMETER-CAR.

1,282,110.

Specification of Letters Patent. Patented Oct. 22, 1918.

Application filed September 8, 1916. Serial No. 118,968.

To all whom it may concern:

Be it known that I, JOHN F. O'CONNOR, a citizen of the United States, residing at Chicago, in the county of Cook and State of Illinois, have invented a certain new and useful Improvement in Dynamometer-Cars, of which the following is a full, clear, concise, and exact description, reference being had to the accompanying drawings, forming a part of this specification.

This invention relates to improvements in dynamometer cars.

One object of this invention is to provide a dynamometer car which may be used under actual operating conditions for testing the actions of draft gears.

Another object of the invention is to provide a dynamometer car having means for making a continuous record of the draw bar pull or tractive effort and substantially instantaneous records of the performance of a gear under sudden impact or draft.

The invention furthermore consists in the improvements in the parts and devices and in the novel combinations of the parts and devices herein shown, described and claimed.

In the drawing forming a part of this specification, Figure 1 is a horizontal sectional view, taken above the floor line of a dynamometer car showing my improvements in connection therewith. Fig. 2 is a vertical, longitudinal sectional view of the car illustrated in Fig. 1 and taken on the line 2—2 thereof. Fig. 3 is an enlarged top plan view of the recording mechanisms and parts immediately associated therewith. Fig. 4 is an enlarged vertical, longitudinal sectional view taken substantially on the line 4—4 of Fig. 3. Figs. 5 and 6 are transverse, vertical sectional views taken on the lines 5—5 and 6—6, respectively of Fig. 3. Fig. 7 is an end elevation of a portion of the car end and casting employed with the draw bar. Fig. 8 is a broken, side elevation of the structure illustrated in Fig. 7. Fig. 9 is a transverse, vertical sectional view taken substantially on the line 9—9 of Fig. 8. Fig. 10 is a diagrammatical view illustrating a sample record card made with one of the recording mechanisms. And Fig. 11 is another diagrammatical view illustrating a sample record card made by the other recording mechanism.

In said drawing, the dynamometer car is shown as provided with channel center sills

20—20 extending from end to end of the car, floor 21, end walls 22, roof 23, side walls 24—24, and a centrally located pit 25, the latter being rendered accessible by steps 26 at each end. The end and side walls of the 60 car are provided with suitable doors 27—27 to permit access to the interior of the car.

The car is provided at each end thereof with a coupler 28, the coupler at one end having a coupler or draw bar extension 29 65 which extends beyond the center of the car and overlaps a coupler or draw bar extension 30, rigidly connected to the coupler at the other end of the car. The details of said draw bar extensions are more particularly 70 hereinafter described.

Each draw bar extension 29 and 30 is preferably provided at its outer end with a box-like casting 31 bolted thereto as indicated at 32, each casting 31 being adapted 75 to receive and rigidly hold the shank of its respective coupler 28. The draw bar extensions 29 and 30 are adapted to reciprocate back and forth freely between the center sills 20 and in order to permit this and at 80 the same time maintain the longitudinal movements of said draw bar extensions in a horizontal line, I have provided a series of links 33 pivotally suspended from cross bars 34 mounted on the tops of the channel center sills. A corresponding number of upwardly extending links 35 are pivotally mounted on cross bars 36 secured to the bottoms of the center sills. Each set of links 33 and 35 (see Figs. 8 and 9) is pivotally connected with links 37 which are arranged horizontally in normal position. The links 37 are pivotally mounted on cross pins 38 extending through the respective draw bar extensions. With the arrangement 85 shown, it is apparent that upon either inward or outward movement of the draw bar extension, the centers of the cross pins 38 thereof will always travel in a horizontal plane due to the parallel motion linkages 100 above described. In the drawings, I have shown two sets of parallel linkages for supporting each of the draw bar extensions, see Figs. 1 and 2.

By referring to Figs. 3, 4 and 5, it will be 105 seen that the channel center sills are each provided with a stop casting 39 on their inner faces, the stop castings 39 each having six main stops 40, 41, 42, 43, 44 and 45. Each of the stop castings is also provided 110

with a corresponding number of limiting stops 140, 141, 142, 143, 144 and 145. Mounted between said stop castings are three sets of springs A, B and C. Each set comprises 5 three springs arranged side by side, the sets A, B and C being arranged in tandem formation, that is, one behind the other in line with the axes of the draw bar extensions. Each set of springs A, B and C is provided 10 at its ends with spring followers 240, 241; 242, 243; and 244 and 245. The draw bar extension 29 is forked at its inner end as indicated at 129, 129 and between the arms or forks 129 extends the inner end of the 15 extension 30. The arms 129 of the draw bar extension 29 are recessed to accommodate the springs and followers and portions of said arms 129 normally engage the followers 240, 241, 242 and 245. The followers 20 241 and 242 are engaged by vertical thimbles 46. The draw bar extension 30 is also recessed to accommodate the springs and followers and it normally engages the followers 240, 243, 244 and 245, said extension 25 30 having a vertical thimble 47 located between the followers 243 and 244.

From the preceding description, it will be seen that, when a pull is exerted on the coupler having the extension 30, the end sets 30 of springs A and C will be compressed, that is, the follower 240 will be moved toward the follower 241 which is held relatively fixed and the follower 244 will be moved toward the follower 245 which also is held 35 relatively fixed. Upon an inward or buffing movement of the same draw bar extension 30, the two sets of springs B and C will be compressed, the follower 243 being forced toward the relatively stationary follower 40 242 by the thimble 47, and the follower 245 moved toward the relatively stationary follower 244. Upon an outward movement of the draw bar extension 29, that is toward the left as viewed in Fig. 3, the sets of springs 45 A and C will be compressed since the followers 241 and 245 will be moved toward the left. Upon an inward movement of the draw bar extension 29, that is, toward the right as viewed in Fig. 3, the sets of springs 50 A and B will be compressed since the followers 240 and 242 will be moved toward the followers 241 and 243, respectively. Each of the draw bar extensions with its coupler, is made extremely heavy and preferably of 9,000 lbs. each since this weight 55 is the weight of a drop hammer ordinarily used in testing draft gears with a drop hammer. The reason for adopting this weight in the present construction will appear hereinafter, although it is apparent that other weights may be used and the proper calculations made therefor.

From the preceding description of the arrangement of springs, followers, and draw bar extensions coöperating therewith, it will

be seen that, in any action either buff or draft, only two sets of the springs will be compressed, thus leaving one set of springs uncompressed and in firm engagement with the draw bar extension not actuated and the 70 car underframe. The function of this arrangement is to prevent any slack or lost motion between the draw bar members and the car, overcome shocks to the car and maintain stability of the various mechanisms. 75

In order to obtain a continuous record of the draw bar pull, I have provided the following arrangement.

By referring more particularly to Figs. 3, 6 and 11, it will be seen that there are two 80 bridge members 48—48 which extend from one arm 129 to the other arm 129 of the draw bar extension 29 and over the draw bar extension 30. Mounted between said bridges 48 is a rotatable cylinder 49 with its 85 axis extending longitudinally of the car. Said cylinder 49 is adapted to have wound therearound a record strip 50 which unrolls from a spindle 51 also rotatably supported by the bridges 48 at the opposite ends thereof. The strip 50 passes over a fixed bed or plate 52 carried by the bridges 48. The cylinder 49 may be rotated by any suitable means at a constant, relatively slow speed as by a clock mechanism indicated diagrammatically at 53 in Fig. 3. It is obvious from the preceding description, taken in connection with the drawing, that the record strip 50 will partake of the movements of the draw bar extension 29. Pivotedly attached 100 to the draw bar extension 30 as indicated at 54 so as to partake of the movements of said extension 30, is a lever 55 having the inner end thereof extending over the record sheet 50. The inner end of the lever 55 carries a 105 pencil or other suitable marking device 56, whereby to make a diagram or record on the sheet 50. When the two draw bar extensions 29 and 30 are in normal position, it is apparent that the pencil 56 will make a line 110 corresponding to the line *r*, *s* on the record strip 50, which is at the center of the strip. The record strip 50 is preferably provided with a series of lines *t*, *t* arranged parallel to the line *r*, *s*, the lines *t* corresponding to 115 the amount of draw bar pull. When a pull is being exerted on either of the draw bar extensions 29 and 30, the pencil 56 will make a record similar to that indicated by the line *v* in Fig. 11. The distance of any point in said line from the line *r*, *s* is proportional to the draw bar pull and by properly spacing the lines *t*, the draw bar pull can be readily estimated. The record sheet 50 is also provided with a series of lines *w* equally spaced 120 and which extend at right angles to the lines *t*. The lines *w* correspond to intervals of time and the use thereof will be readily understood by those skilled in the art. It 125 will be noted in Fig. 11 that a part of the 130

record *v* is to one side of the line *r*, *s* and another part to the opposite thereof. These two portions correspond, one to a relatively separating movement of the draw bar extensions 29 and 30, and the other to a relative approach of said draw bar extensions 29 and 30.

In order to record the work done during any blow or pull, I have provided the following mechanism.

Referring more particularly to Figs. 3, 4, 5 and 10, it will be seen that there is a bridge 58 which extends from one arm 129 to the other arm 129 over the draw bar extension 30. Pivotaly mounted on said bridge 58 is a lever arm 59 which, at its free end, carries a pencil 60. The pencil 60 is adapted to coöperate with a record sheet 61 carried by a cylinder 62 mounted as hereinbefore described. Normally, the pencil 60 is kept out of engagement with the sheet 61 by means of a spring 63. The lever 59 is, however, provided with an armature 64 which is adapted to coöperate with a magnet 65 carried by said bridge 58. Suitable electrical connections are made with the magnet 65 so that the current may be caused to energize the magnet at any instant to thereby pull down the lever 59 and cause engagement of the pencil 60 with the record sheet 61. The cylinder 62 is rotatably carried by a suitable casting 66 rigidly mounted on the draw bar extension 30, the axis of the cylinder 62 extending parallel to the axis of the draw bar extension 30. The shaft 67 which carries the cylinder 62 is provided at one end with a beveled gear 68 which meshes with another beveled gear 69 carried on the inner end of a flexible shaft 70. The shaft 70 is connected at its opposite end with the armature of a motor indicated diagrammatically at 71, the motor being mounted on a part of the car underframe. Also carried by the draw bar extension 30 is a speed indicator 72 which is connected by a belt 73 to the shaft 67 that carries the cylinder 62.

The cylinder 62 is driven at relatively high speed from the motor 71, the speed being determinable by means of the speed indicator 72, as will be apparent. At the instant a blow is being transmitted to either of the couplers or draw bars, the operator will energize the magnet 65, thus causing the pencil to engage the rapidly rotating record sheet 61. Without any relative movement between the draw bar extensions 29 and 30, the pencil 60 will make a line corresponding to that referenced *x* in Fig. 10. As soon as the blow is transmitted to the draw bar extension, a record will be made corresponding to that indicated at *y* in Fig. 10. In actual practice, the time required for making this record will be a relatively small fraction of a second. I do not deem it necessary to enter into a detailed descrip-

tion of the recording mechanism above referred to since the same is fully described and claimed in my Patent No. 1,217,984, issued March 6, 1917, for improvement in means for recording actions of railway draft gears, to which reference is hereby made. As described in said patent No. 1,217,984, the recording mechanism is designed for coöperation with a hammer of 9,000 lbs., for which reason the draw bar and draw bar extensions in the dynamometer car herein described are made of similar weight, to facilitate reading of the record cards.

The method by which the record is actually read and the work performed, calculated, is described more fully in my Patent No. 1,225,687, issued May 15, 1917, for improvement in indicators.

From the preceding description, it will be seen that, when a sudden shock is transmitted to either of the draw bars and its extension, a certain amount of work will necessarily be performed in accelerating the 9,000 lb. draw bar and its extension from a relatively zero velocity to a higher velocity. Knowing the weight which is thus accelerated and from the record card made of the operation, the time during which the acceleration takes place, the rate of acceleration can be determined and also the amount of work performed or the rate of doing the work calculated. With the recording mechanism for registering the draw bar pull, a continuous record is provided which shows the operating conditions of the car at all times during a continuous run. It will also be noted that the two sets of recording mechanisms are so arranged that they coöperate with both draw bars and extensions.

I have herein shown and described what I now consider the preferred means of carrying out my invention, but the same is merely illustrative and as will be apparent to those skilled in the art, various changes and modifications may be made in the details of construction and arrangement of parts without departing from the spirit of the invention.

I contemplate all changes and modifications that come within the scope of the claims appended hereto.

I claim:

1. In a dynamometer car, the combination with a yieldingly mounted draw bar and extension of a predetermined relatively heavy weight, of mechanism associated with said draw bar and carried by the car for recording the rate of acceleration of the draw bar and its extension when a sudden shock is transmitted thereto.

2. In a dynamometer car, the combination with a pair of longitudinally movable draw bars having extensions, the draw bars and extensions being yieldingly mounted with

respect to the car and each being of a predetermined, relatively heavy weight, of mechanism associated with both of said draw bars and extensions and the car for 5 recording the rate of acceleration of either draw bar and its extension when a sudden shock is transmitted thereto.

3. In a dynamometer car, the combination with a pair of oppositely arranged draw 10 bars, each yieldingly longitudinally movably mounted with respect to the car proper, of a single recording mechanism associated with both of said draw bars and adapted to indicate the draw bar pull of either.

15 4. In a dynamometer car, the combination with a pair of oppositely arranged draw bars, each yieldingly longitudinally movably mounted with respect to the car proper, of an intermittently operable recording mechanism.

20 5. In a dynamometer car, the combination associated with both of said bars and adapted to register the rate of acceleration of either of said draw bars upon transmission of a sudden shock thereto.

25 6. In a dynamometer car, the combination with a pair of draw bars having extensions, said draw bars and extensions being each of a known heavy weight, of means for supporting said draw bars and extensions to permit independent longitudinal movement 30 thereof and at the same time maintain the draw bars and extensions in the same horizontal plane.

35 7. In a dynamometer car, the combination with a pair of oppositely arranged draw bars and extensions each independently longitudinally movable with respect to the car proper, the extensions overlapping each other, of recording mechanism associated with said draw bar extensions, said mechanism including elements rigid with respect to a portion of one draw bar extension and other elements movable in unison with the other draw bar extension whereby relative movement between the draw bar extensions is 45 reproduced on the recording mechanism.

40 8. In a dynamometer car, the combination with a pair of draw bars having extensions and being of a predetermined, relatively heavy weight, said extensions being overlapped, of cushioning means interposed between both the draw bars and the car, and recording mechanism associated with the draw bars, said recording mechanism including elements movable in unison with one 45 draw bar and elements movable in unison with the other draw bar, whereby relative movement between the draw bars is indicated by the recording mechanism.

40 9. In a dynamometer car, the combination with two relatively longitudinally movable heavy members adapted to be movable in unison with the movements of respective couplers at the ends of the car and each independent of the car, of a recording mech-

anism associated with said members, said 65 recording mechanism being adapted for operations during short intervals of time and arranged to indicate the amount and rate of relative movement between said two members.

70 10. In combination, a car having sills, stop castings secured to said sills, said stop castings being each provided with three sets of main stops arranged longitudinally one behind the other, of two members mounted 75 between said stop castings, one of said members being arranged for movement in unison with a coupler at one end of the car and the other member adapted for movement in unison with a coupler at the opposite end of the car, three sets of springs and followers operatively associated with said stop castings and said members, and means associated with said members arranged to actuate two sets of springs and followers 80 only upon movement of either of said members:

85 11. In combination, a car having sills, stop castings secured to said sills, said stop castings being each provided with three sets of main stops arranged longitudinally one behind the other, of two members mounted 90 between said stop castings, one of said members being arranged for movement in unison with a coupler at one end of the car and the other member adapted for movement in unison with a coupler at the opposite end of the car, three sets of springs and followers 95 operatively associated with said stop castings and said members, and means associated with said members arranged to actuate two sets of springs and followers only upon movement of either of said members, and recording mechanism associated with 100 said members to indicate their movement relatively to each other.

105 12. In a dynamometer car, the combination with a draw bar and extension at one end of the car, a draw bar and extension at the opposite end of the car, said extensions 110 overlapping each other near the center of the car, of a bridge rigidly secured to one of said draw bar extensions, said bridge having an electrically controlled marker carried thereby, a rapidly rotating cylinder 115 mounted on and carried by the other draw bar extension and movable bodily in unison therewith, and a motor carried by a portion of the car underframe and arranged to drive said cylinder, there being a flexible driving 120 connection between the motor and said cylinder.

125 13. In a dynamometer car, the combination with a horizontally movable member of 9,000 lb. weight and moving in accordance with the movements of a coupler, of an intermittently operable recording mechanism associated with the car and said member and

arranged to indicate the relative movements therebetween, said mechanism including a rapidly moving sheet, a stylus normally out of engagement therewith, and means coacting with said stylus for placing the latter in operative engagement with the sheet at any desired instant to thereby record the rate of

acceleration of said 9,000 lb. member when a sudden shock is transmitted thereto.

In witness that I claim the foregoing I 10 have hereunto subscribed my name this 5th day of Sept. 1916.

JOHN F. O'CONNOR.
